[57] CLAIM

The ornamental design for a headgear for faceshield, as
shown and described.

DESCRIPTION

FIG. 1 is a front and right side perspective view of a
headgear for faceshield showing our new design;
FIG. 2 is a side elevational view thereof, the opposite
side view being a mirror image of that shown, the
broken lines are for illustrative purposes only;
FIG. 3 is a top plan view thereof, the bottom plan view
being a mirror image of that shown;
FIG. 4 is a front elevational view thereof;
FIG. 5 is a rear elevation view thereof.
